CONTAINER RACK

Charlie J. Ventura, 5308 Miller Ave., Dallas, Tex.
Filed Nov. 8, 1963, Ser. No. 322,553
12 Claims. (Cl. 211—71)

This invention relates to new and useful improvements in container racks.

This is a continuation-in-part of the copending application Serial No. 302,086, filed August 14, 1963, now abandoned.

One object of the invention is to provide an improved rack of economical and durable construction having a minimum of parts and which is simple of erection for supporting containers, such as garbage cans on a fence or wall interchangeably.

A particular object of the invention is to provide an improved container rack having means for securing it to the top rail and supporting posts of fences of the type having pipe or cylindrical posts and pipe top rails and including a strong and effective structure for securing the supporting elements of the rack in position on the fence, whereby the containers to be supported by the rack are held at an elevated position above the ground and in position for access thereto from either side of the fence.

Still another object of the invention is to provide a container rack of the character described having means for supporting the portion of the same spaced outwardly from the fence against downward forces whereby the rack is positively held in an upright position and the rack will not sag or permit the containers to be dislodged therefrom or to press against the fence or building structure to which the rack is secured.

Still another object of the invention is to provide in a container rack of the character described means for firmly and securely securing the rack to the fence or wall structure and which is provided with supplemental supporting means for supporting the outer portion of the rack if desired.

A principal object of the invention is to provide a container rack particularly designed to support garbage cans and adapted to retain the same in an elevated position wherein access thereto by cats, dogs and other roving animals is prevented, and upsetting or removing the tops or covers and spreading the garbage over the adjacent area is prevented.

A further object of the invention is to provide in a rack of the character described means for securing the covers for the containers supported thereby to the rack whereby the covers will not be lost or damaged.

A still further and particular object of the invention is to provide a rack of the character described which includes means for positively supporting and holding garbage containers therein and which is economical but durable and strong in its construction.

Another object is to provide a rack of the character described which is easily and economically fabricated from a minimum of parts and material and without the use of expensive dies or jigs.

Still another object is to provide a rack of the character described including a receptacle section having a pair of top circular retaining rings through which the garbage cans and the like may be inserted into and removed from the rack, a pair of horizontal spaced arm portions secured to the rings and a vertical central portion spaced below the horizontal arms and secured to the rings by a reinforcing or brace member which is secured to the rings and to the vertical central portion whereby the receptacle is of rigid structure and is rigidly securable to a fence or a wall.

Additional objects and advantages of the invention will be readily apparent from the reading of the following

2

description of a device constructed in accordance with the invention, and reference to the accompanying drawings thereof, wherein:

5 FIGURE 1 is a perspective view of a container rack constructed in accordance with the invention mounted on a fence;

FIGURE 2 is a top plan view of the container rack of FIGURE 1;

10 FIGURE 3 is a front elevation of the container rack of FIGURE 1;

FIGURE 4 is a vertical fragmentary sectional view taken on the lines 4—4 of FIGURE 3;

15 FIGURE 5 is a fragmentary isometric view of a portion of one horizontal arm of the rack showing the cover chain swivel connector;

FIGURE 6 is a side elevation of a slightly modified form of the rack showing the same mounted on a wall structure;

20 FIGURE 7 is a perspective view of a modified form of a container rack constructed in accordance with the invention mounted on a fence;

FIGURE 8 is a top plan view of the container rack of FIGURE 7;

25 FIGURE 9 is a front elevation of the container rack of FIGURE 7;

FIGURE 10 is a vertical fragmentary sectional view taken on line 10—10 of FIGURE 9;

30 FIGURE 11 is a fragmentary isometric view of a portion of one horizontal arm of the rack showing the cover change swivel connector; and

FIGURE 12 is a side elevation showing the rack of FIGURE 2 mounted on a wall or a wood fence.

In FIGURES 1 through 6 of the drawings, the numeral 10 designates generally a container rack which is adapted 35 to be mounted on the upright posts 11 and horizontal railing 12 of a wire mesh or chain link fence 13. While the fence is shown and described as being a chain link type having the metallic posts and tubular top rail, the fence might be of any other usual type, as will be readily apparent hereinafter. Obviously, the rack may be secured on the fence of a back yard of a residence or other place on either side of the fence and still be readily accessible to both the householder and to the garbage collection personnel.

40 As is clearly shown in the drawings, the rack has a generally T-shaped supporting frame 15 having upper horizontal arm portions or arms 16 and 17 which are arcuate in cross section extend about the railing and may be formed of any desired material but are preferably sections of tubing or pipe. The vertical upright central portion 18 of the frame is likewise preferably formed of substantially semi-cylindrical sections of metal, so that the upright portion also is adapted to engage around the usual post 11 of the fence. The vertical portion 18 com-

50 prises a semi-cylindrical lower member 19 and upper slightly larger arcuate member 20 surrounding and overlying the upper end portion of the lower member 19. The extreme upper end portion of the member 20 is flattened and bent outwardly and then upwardly as at 21, and is

55 then flattened throughout the major portion of its length as shown at 22 to provide a plate which is curved rearwardly at its extreme upper end and this rearwardly curved upper end portion 23 has the inner ends of the semi-cylindrical or arcuate arms 16 and 17 of the horizontal portion of the frame welded thereto. An aperture 24 is formed in the rearwardly curved upper portion 23 of the plate and this aperture is adapted to accommodate the usual cap piece 25 of the fence post.

60 The arms 16 and 17 of the frame are secured to the fence rail by screw band clamps 28a and 28b of any suitable well known type, said clamps extending around the pipe forming the upper rail 12 of the fence and also

around the concave arcuate arms 16 and 17 of the T-shaped frame, whereby when the clamps are tightened by turning the tightening screws thereof, the arms are securely held in place on the railing of the fence. Similarly, a larger screw band clamp 28c is used to secure the upright member 18 of the T-frame to the fence post 11 and this clamp may also be tightened as desired. If the concave arms 16 and 17 and the concave upright central portion 18 of the T-shaped frame do not closely and tightly fit the posts and railings, it is obvious that the clamps 28a, 28b and 28c will force the arms into close engagement with the posts and railings and hold the T-shaped frame rigidly supported by the fence.

The receptacle section 29 of the rack comprises an outwardly then upwardly and then inwardly bent substantially C-shaped vertical member 30 having the inner end of its lower portion 31 welded to the lower portion of the lower member 19 of the upright portion of the frame, and having its vertical upright central portion 32 extending parallel to and spaced outwardly from the vertical upright of the frame and its upper inwardly extending arm portion 33 welded or otherwise suitably secured at its inner end to the upper portion of the plate 22 of the member 20. A pair of parallel horizontally extending supporting rods or members 40 and 41 are secured in their mediate portions to the upper side of and welded to the lower outwardly extending portion 31 of the C-shaped member 30, and at their outer ends the supporting members 40 and 41 are bent upwardly providing upright arms 42a and 42b and 43a and 43b, respectively, the upright arms of the two members extending substantially parallel to each other, with the arms at the opposite ends of each member extending slightly divergently outwardly from their lower ends toward their upper ends. The extreme upper end of each of the upright arms is secured to one of a pair of circular retaining rings 50 and 51 which are welded on opposite sides of the inwardly extending upper portion 33 of the C-shaped member 30. At the point of contact of the ring 50 with the laterally extending arm 17 of the supporting frame the ring is welded thereto as shown at 52, and the upper ends of the arms 42a and 43a are welded to the under side of the ring as shown at 53 and 54. The ring 51, which is welded to the opposite side of the upper portion 33 of the C-shaped member is likewise welded, as is shown at 57, at the point of tangency of said ring with the horizontal arm 16 of the supporting frame 15. The upper ends of the upright arms 42b and 43b are welded as shown at 58 and 59 to the under side of the retaining ring 51. With the elements so secured together, it will be seen that the receptacle section 29 of the rack is rigidly secured to and supported by the T-shaped frame 15 thereof.

The size of the rings 50 and 51 is such as to accommodate a wide range of garbage cans or other containers and the horizontal supporting rods 40 and 41 are adapted to be engaged by the bottoms of the cans and to support the cans at a position above the ground, as clearly shown in FIGURE 1. Obviously, the rings will prevent the cans from being easily displaced from the rack and the upright arms 42a and 43a and the upright arms 42b and 43b support the outer ends of the rods 40 and 41 and prevent the cans from sliding off said rods and off the rack. It will be readily apparent that, if desired, a diagonal brace 69, shown in dotted lines in FIGURE 1 and in full lines in FIGURE 6, may be secured between the inner end of the upper portion 33 of the C-shaped member 30 and the outer end of the lower portion 31 of said C-member to provide a still further support for the outer portions of the receptacle section, and this diagonal brace will further prevent the cans or containers supported by the rack from being displaced from position thereon.

A chain 65 having a swivel 66 at one end has said swivel secured by means of an I-bolt or ring 67 to the outer end of the arm 16. The other end of the chain 65 is provided with an eye 68 which may be secured by bolts 69 or any

other suitable means to the top T of the garbage can C for permitting removal of the cover or top from the can and to retain the top in an elevated position off the ground and in place for subsequent replacement on the can after the can has been emptied by the garbage collector.

A similar chain 65a is secured to the outer end of the arm 17 of the T-shaped frame and is connected by a swivel 66a to an I-bolt or ring 67a on the outer end of the arm 17. The opposite end of the chain 65a may be secured to the top of the garbage can C by a bolt or the like in the same manner as the chain previously described.

A tubular sleeve 75 is secured by welding or otherwise to the lower end portion of the upright central portion 32 of the C-shaped member 30 and is adapted to receive an elongate vertically extending supporting post or rod 77 which extends through the sleeve and is slidable therein. The lower end of the rod may engage a brick or stone or other base member 78 buried or secured in the ground therebeneath to provide an additional support and steady force on the outer portion of the rack if desired. The rod 77 is provided with a plurality of longitudinally spaced transverse apertures or holes 76 which are adapted to register and align with transverse openings 79 formed in the sleeve 75, whereby a bolt or pin 80 may be disposed in the openings in the sleeve and extend through the desired suitable aperture in the rod to hold the rod in position supporting the outer portion of the rack. Of course, it will be seen that the rod 77 is not necessary and need not be included as a part of the rack but provides additional support for the outer portion thereof when used.

While the rack previously described has been illustrated and described as secured to the usual metallic post and tubular rail wire mesh fence structure, it is readily apparent that the T-shaped frame member of the rack may be secured by nails or screws to other types of fences or to a vertical wooden wall of a building or the like, if desired. Such an installation is shown in FIGURE 6, wherein the upright member 18 and the horizontal arms 16 and 17 of the frame 15 are disposed in abutting relationship to the wall W of a fence of building structure and nails or bolts or screws 85 are driven through suitable apertures 19a and 20a formed in the uprights and through suitable apertures 16a and 17a formed in the horizontal arms 16 and 17, respectively. The nails or screws will extend through the apertures in the frame members and engage in the wall to hold the frame securely in place thereon. In this installation, the brace member 69 is shown in place secured at its lower end 60a to the lower end of the upright member 32 of the C-frame member 30 as has been previously described and secured at its upper end 66b to the plate member 22 of the upper section 29 of the upright frame member 18. In this installation, the rod 77 is not shown and there is no auxiliary or supplemental support for the outer portion of the rack, though such rod may be used here also, if desired. Otherwise, the rack is identical to the rack form first described but is installed on a different supporting structure.

It will therefore be seen that the rack is simple in structure and may be fabricated of metal rods or tubes; is a rigid, sturdy, durable and of simple construction, open and easily cleaned, which supports the garbage cans or other containers at an elevated position above the ground and readily accessible for handling.

It will also be seen that the covers for the containers are held in place for ready access for use; and are held supported off the ground by the chains so that the tops will not become damaged, run over or lost.

It will also be seen that the rack is readily adaptable for all types of fences and other supports and is provided with supplemental supporting means.

Referring now particularly to FIGURES 7 through 12 of the drawings, the numeral 110 designates generally a modified can or container rack which is adapted, like the

container rack 10, to be mounted on an upright post 11 and a horizontal railing 12 of a wire mesh or chain-link fence 13. The rack 110 includes a pair of spaced horizontal arm portions or arms 116 and 117 which are arcuate or semi-cylindrical in cross section to extend about or receive the railing 12 and may be formed of any desirable material, such as sections of tubing or pipe. The vertical upright central portion 118 of the rack is likewise preferably formed of a substantially arcuate or semi-cylindrical section of metal so that the upright central portion 118 is adapted to extend about or receive the usual vertical post 11 of the fence. The railing arms 116 and 117 and the central vertical post portion 118 are securable to the railing and to the post 11 of the fence by screw clamps 128a, 128b and 128c, respectively, which may be of any suitable type, such as that disclosed in U.S. Letters Patent No. 2,452,806 and No. 2,386,629.

The rack also comprises a substantially C-shaped member 130, the inner end of whose horizontal bottom portion 131 is welded to the lower portion of the central post portion 118, whose outer central portion 132 extends parallel to and is spaced outwardly from the post portion 118, whose top horizontal portion 133 extends horizontally above its bottom portion 131, and whose downwardly inclined portion 134 extends from the inner end of the top portion to the post portion 118 and is welded thereto at a location spaced above the end of the bottom portion thereof.

A pair of spaced parallel horizontal supporting rods or members 140 and 141 extend perpendicularly over the bottom portion 131 of the C-shaped member 130 and are welded thereto. The outer ends of the supporting members 140 and 141 are bent upwardly providing upright arms 142a and 142b, and 143a and 143b, respectively. The upright arms 142a and 143a extend substantially parallel to each other and the upright arms 142b and 143b extend substantially parallel to each other. The arms at the opposite ends of each member extend divergently upwardly.

The upper end of each of the upright arms is secured to one of a pair of horizontal annular retaining members or rings 150 and 151 welded to opposite sides of the top horizontal portion 133 of the C-shaped member which extends therebetween. The upper ends of the upright arms 142a and 143a are welded to the underside of the ring 150 while the upper ends of the upright arms 142b and 143b are welded to the underside of the retaining ring 151. The ring 150 is welded, as at 158, to the horizontal railing arm 117 at its location of tangential contact therewith, and is welded, as at 159 to the top horizontal portion 133 at its location of tangential contact therewith. The ring 151 is similarly welded, as at 160, to the horizontal railing arm 116 at the location of its tangential contact therewith and is welded, as at 161, to the top horizontal portion 133 at the location of its tangential contact therewith.

It will be apparent that the rings 150 and 151 and the top horizontal portion 133 of the C-shaped member 130 lie in a common horizontal plane which intersects the horizontal arms 116 and 117.

The size of the rings 150 and 151 is such as to accommodate a wide range of sizes of garbage cans or other containers and the horizontal supporting rods or members 140 and 141 are adapted to be engaged by the bottoms of such cans to support the cans above the ground as shown in FIGURE 1. The rings prevent the cans from being easily displaced from the rack and the upright arms 142a and 142b and 143a and 143b support the outer ends of the rods 140 and 141, respectively, and prevent the cans from sliding off the rack. The inclined portion 134 of the C-shaped member 130 is disposed between the cans held by the rings 150 and 151 and also helps prevent their movement.

The chain 165 has one end connected by a swivel 166 and a ring 167 to the outer end of the arm 116. The

other end of the chain is provided with an eye 168 which may be secured by a bolt 169 or suitable means to the top T of a garbage can C positioned in the ring 151. The chain 165 retains the top in an elevated position off the ground after it has been taken off the can and in position for subsequent replacement on the can after the can has been emptied or loaded. A similar chain 165 is similarly secured to the horizontal arm and to a top T of another can which is receivable in the retaining ring 150.

10 The clamps 128a and 128b extend above the railing, the rings 151 and 152 and the horizontal arms 116 and 117, respectively, to rigidly secure the arms 116 and 117 to the railing. The clamps 128a and 128b are held against lateral movement on the railing due to the curvature of

15 the rings 150 and 151 through which they extend and through which they engage. The clamp 128c extends about the post 11 and the central portion 118 between the bottom and inclined portions 131 and 134 of the C-shaped member 130.

20 A tubular sleeve 175 is secured by any suitable means, as by welding, to the lower end portion of the upright central outer portion 132 of the C-shaped member and is adapted to receive an elongate vertically extending supporting post or rod 177 which extends therethrough and

25 is slidable therein. The lower end of the rod engages a brick, stone, or other base member 178 buried or secured in the ground therebeneath to provide additional steady support and force on the outer portion of the rack as is desired. The rod 177 is rigidly secured to the tubular sleeve in any vertically adjusted position relative thereto by means of a set screw 180 threaded in a suitable lateral bore of the vertical sleeve.

30 It will now be seen that the container rack is securable to a fence having a horizontal railing and a vertical post at two spaced points or locations of the railing by the railing arms 116 and 117 and to the post at a point spaced below and between the arms by the central upright section 118 so that the container is held against displacement in any direction relative to the fence.

35 It will further be seen that the arcuate or semi-cylindrical horizontal arms 116 and 117 which extend about the railing 12 tend to hold the rack against vertical movement by their engagement with the railing, the clamps 128a and 128b being necessary not to support the arms against downward or upward movement on the railing but to prevent the horizontal outward movement of the arms out of telescoping position on the railing.

40 The arms 116 and 117 and the central vertical portion 118 of the rack are each provided with one or more spaced apertures 181 through which nails, bolts or screws 185 may extend to rigidly secure the rack to a wall W to a fence or building structure so that the rack 110 like the rack 10 may be secured to a wall as well as to the railing and a post of the usual wire mesh or chain-link fence.

45 It will now be seen that the main difference between the modified rack 110 and the rack 10 is the omission of the member 20 and the provision of the diagonal or downwardly inclined portion 134 of the substantially C-shaped member 130 which is secured to the central portion 118. The rack having the structure of rack 110 is preferred since the member 20 of the rack 10 is of a peculiar configuration and its manufacture requires the use of an expensive die as well as the additional stock or material of which it is fabricated.

50 It will further be seen that both the rack 110 and the rack 10 include a pair of rings disposed in a common horizontal plane having supporting means which extends below the rings to support the container position in the rings, means such as the arcuate members 16 and 17 and 116 and 117 providing a pair of spaced concave surfaces having a common horizontal axis of curvature and positionable about a horizontal member such as a railing 12, and that the supporting means for the containers has secured thereto means, providing a concave surface having

a vertical axis of curvature, such as the arcuate portions 18 and 118 spaced below and between the horizontal spaced concave surfaces and the rings, and that all of the concave surfaces face outwardly in the same direction from the rings.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A container rack adapted to be detachably mounted on a supporting member and including: a frame having an upright member and a laterally extending cross member at its upper end; a supporting element disposed outwardly from and extending parallel to the upright element of the frame member and having inwardly extending portions secured to said upright member; annular receiving members secured to the cross member of the frame and to the outwardly extending portion of the supporting element; and a horizontally extending supporting member secured to the supporting element and extending substantially parallel to the cross member of the frame in a plane spaced substantially below said cross member; said supporting member having upwardly extending outer portions connected at their upper ends with the annular receiving members and secured thereto to provide means for receiving and supporting a container.

2. A container rack adapted to be detachably mounted on a supporting member and including: a substantially T-shaped frame having an upright member and a pair of laterally extending arm cross members; a receptacle section having a C-shaped supporting element having a vertical portion disposed outwardly from and extending parallel to the upright element of the frame member and upper and lower horizontal portions secured at their inner ends to said upright member, a pair of annular receiving members secured to the arms of the frame and to the upper horizontally extending portion of the supporting element; and a pair of laterally spaced horizontally extending supporting members secured to the lower horizontally extending portion of the supporting element and extending substantially parallel to the arms of the frame in a plane spaced substantially below said arms; said supporting members having upwardly extending outer arm portions connected at their upper ends with the annular receiving members and secured thereto to provide means for receiving and supporting a container.

3. A rack of the character set forth in claim 1, including: a tubular sleeve on the vertical portion of the supporting element; and a rod slideable in said sleeve and adapted to engage a supporting surface below the assembly to support the outer portion of the receptacle section, and means for securing said rod and said sleeve at adjusted positions in said sleeve.

4. In a rack of the character set forth in claim 1, flexible supporting members carried by each of the arms of the frame and pivotally secured thereto, said supporting flexible members having means for securing them to the cover of containers supported by the receptacle section for retaining such covers accessible for use.

5. In a rack of the character set forth in claim 1, and clamp means for securing said upright and said arms of said frame member to a supporting structure.

6. In a rack of the character set forth in claim 2, clamp means for securing said upright and said arms of said frame member to a supporting structure.

7. A container rack adapted to be detachably mounted on a supporting member and including: a substantially T-shaped frame having an upright member and a pair of laterally extending arm cross members; a receptacle section having a C-shaped supporting element having a vertical portion disposed outwardly from and extending parallel to the upright element of the frame member and

upper and lower horizontal portions secured at their inner ends to said upright member, a pair of annular receiving members secured to the arms of the frame and to the upper horizontally extending portion of the supporting element; and a pair of laterally spaced horizontally extending supporting members secured to the lower horizontally extending portion of the supporting element and extending substantially parallel to the arms of the frame in a plane spaced substantially below said arms; said supporting members having upwardly extending outer arm portions connected at their upper ends with the annular receiving members and secured thereto to provide means for receiving and supporting a container; and a diagonal brace member secured at its upper end to the upper end of the upright and at its lower end to the outer portion of the lower member of the C-shaped supporting member of the receptacle section.

8. A container rack of the character set forth in claim 2, wherein: the upright member of the frame has a plate section at its upper end disposed in a laterally outwardly offset position with respect to the remainder of the upright portion and secured at its upper end to the horizontal arms for connecting the upright member and the horizontal arms, said offset portion of the plate member providing for receiving the caps of fence posts.

9. A rack including: a pair of horizontal annular members disposed in a common horizontal plane; means secured to and extending below said annular members for supporting containers positionable in said annular members; a pair of spaced arcuate portions having a common horizontal axis of curvature secured to said annular members and positionable about a horizontal supporting member; and a vertical arcuate portion having a vertical axis of curvature and secured to said means and spaced below and between said pair of arcuate means and said annular members and positionable about a vertical supporting member, said arcuate portions having concave surfaces facing outwardly in the same direction from said annular members.

10. A rack including: a pair of horizontal annular members disposed in a common horizontal plane; means secured to and extending below said annular members; a pair of spaced arcuate portions having a common horizontal axis of curvature secured to said annular members and positionable about a horizontal supporting member; and a vertical arcuate portion having a vertical axis of curvature and secured to said means and spaced below and between said pair of arcuate means and said annular members and positionable about a vertical supporting member, said arcuate portions having concave surfaces facing outwardly in the same direction from said annular members; clamp means extendable through said annular members and about said arcuate portions and a supporting member on which said horizontal arcuate portions are positionable for rigidly securing said arcuate portions to the supporting members.

11. A rack including: a pair of horizontal annular members disposed in a common horizontal plane; means secured to and extending below said annular members for supporting containers positionable in said annular members; a pair of spaced arcuate portions having a common horizontal axis of curvature secured to said annular members and positionable about a horizontal supporting member; and a vertical arcuate portion having a vertical axis of curvature and secured to said means and spaced below and between said pair of arcuate means and said annular members and positionable about a vertical supporting member, said arcuate portions having concave surfaces facing outwardly in the same direction from said annular member, said means secured to said annular members comprising a pair of horizontal parallel spaced supporting members spaced below said annular members and having arm portions extending upwardly to and secured to said annular members, and a substantially C-shaped member having a bottom horizontal portion whose inner end is

rigidly secured to said vertical arcuate portion, said bottom horizontal portion being rigidly secured to said horizontal supporting members, said C-shaped member having a horizontal outer vertical portion extending upwardly, a top horizontal portion extending between and rigidly secured to said annular members and a downwardly extending portion extending from the inner end of said top horizontal portion whose lower end is rigidly secured to said vertical arcuate portion at a location spaced from said bottom horizontal portion.

12. A rack including: means providing a pair of rings disposed in a common horizontal plane; supporting means secured to said rings and extending below the rings for supporting the containers positionable in said rings; means providing a pair of spaced concave surfaces having a common horizontal axis of curvature secured to said rings and positionable about a horizontal supporting member; and means providing a concave surface having a vertical

axis of curvature secured to said supporting means and spaced below and between said pair of spaced concave surfaces and said rings, said arcuate surfaces facing outwardly in the same direction from said rings.
